UNITED STATES PATENT OFFICE.

ROBERT B. GRIFFIN, OF NEW YORK, N. Y., ASSIGNOR TO ROBERT GRIFFIN CO., OF NEW YORK, N. Y., A CORPORATION OF NEW YORK.

DESIGN FOR WALL-PAPER.

46,729.

Specification for Design.

Patented Dec. 8, 1914.

Application filed September 14, 1914. Serial No. 861,728. Term of patent 3½ years.

To all whom it may concern:

Be it known that I, ROBERT B. GRIFFIN, a citizen of the United States, residing at New York, in the county of New York and State of New York, have invented a new, original, and ornamental Design for Wall-Paper, of which the following is a specification, reference being had to the accompanying drawing, forming a part thereof.

The drawing shows a plan view of a unit of the design which may be repeated as many times as desired.

I claim—

The ornamental design for wall papers as shown.

ROBERT B. GRIFFIN.
